UNITED STATES PATENT OFFICE.

THOMAS ADAMS, JR., OF HIGHLAND, NEW YORK.

FOLDING CLOTHES-RACK.

SPECIFICATION forming part of Letters Patent No. 338,011, dated March 16, 1886.

Application filed March 21, 1885. Serial No. 159,628. (No model.)

To all whom it may concern:

Be it known that I, THOMAS ADAMS, Jr., a citizen of the United States, and a resident of Highland, in the county of Ulster and State of New York, have invented certain new and useful Improvements in Folding Clothes-Racks; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view showing my improved clothes rack extended and ready for use. Fig. 2 is an end view of the same, with dotted lines showing the arms in position ready to be folded; and Fig. 3 is a perspective view showing the device folded for storage or transportation.

The same letters refer to the same parts in all the figures.

This invention relates to folding clothes-racks; and it has for its object to provide a device of this class which shall possess points of simplicity, durability, inexpensiveness, and general efficiency.

With these ends in view it consists in the improved construction, arrangement, and combination of parts, which will be hereinafter fully described, and particularly pointed out in the claims.

In the drawings hereto annexed, A A designate the heads or ends of my improved clothes-rack, which consist of horizontal bars B B, having centrally-located vertical uprights, C C, the upper ends of which, as well as the ends of the horizontal bars B B, are connected by transverse bars or braces D and E E.

Upon the ends of the arms E E, adjoining the inner sides of the cross-pieces B B, are pivoted arms F F, the outer ends of which are connected by transverse braces G G, upon which are pivoted additional arms, H H, connected by braces I I, the ends of which are constructed with dovetailed or arrow heads J.

K K are the leg-frames, which are hinged to the under sides of the cross-pieces B B of the heads or ends in such a manner as to be capable of being folded inwardly, as will be clearly seen with reference to Fig. 3 of the drawings. The leg-frames are provided on their outer sides, near their upper ends, with dovetailed recesses L L, into which the ar-

row-heads J J may be inserted when the said leg-frames and the pivoted arms of the device are extended, as shown in Fig. 1 of the drawings, thereby bracing and securing the parts in an extended position.

From the foregoing description, taken in connection with the drawings hereto annexed, the operation and advantages of this invention will be readily understood. The construction is simple and inexpensive, the device is light and durable, and it may, when not in use, be folded, as shown in Fig. 3, so as to occupy but little space. When the device is thus folded, the leg-frames may be secured by means of a hook, M, hinged to one of them, and adapted to be connected with a staple, N, secured to one of the cross-braces D.

I would have it understood that in the manufacture of this device I do not wish to limit myself to the identical or precise construction herein shown and described, but reserve to myself the right to all modifications which may be resorted to without departing from the spirit of my invention.

Having thus described my invention, I claim and desire to secure by Letters Patent of the United States—

1. In a folding clothes-rack, the combination of the heads or ends, the inwardly-folding leg-frames hinged to the under edges of the same, and the pivotally-connected arms connected by cross-braces, and adapted to be connected with the leg-frames when the latter are extended, substantially as herein described, for the purpose shown and specified.

2. In a folding clothes-rack, the combination of the heads or ends connected by cross-braces, the inwardly-folding leg-frames hinged to the under edges of said heads or ends, arms pivoted to the outer braces, connected to the heads or ends, and having their free ends connected by cross-braces, arms pivoted upon the said cross-braces, and having their free ends connected by cross-braces provided with dovetailed or arrow heads, and notches in the leg-frames adapted to receive the said heads, substantially as herein described, for the purpose shown and specified.

In testimony that I claim the foregoing as my own I have hereunto affixed my signature in presence of two witnesses.

Witnesses: THOMAS ADAMS, JR.
SAM'L CRAWFORD,
GEORGE SAXTON.
